CLAIM

The ornamental design for a double-headed hand-held power tool for grinding, drilling, screwing, and other operations on workpieces, as shown and described.

DESCRIPTION

1. Double-headed hand-held power tool for grinding, drilling, screwing, and other operations on workpieces

- 1.1 : Perspective
- 1.2 : Perspective
- 1.3 : Front
- 1.4 : Back
- 1.5 : Left
- 1.6 : Right
- 1.7 : Top
- 1.8 : Bottom

A double-headed hand-held power tool is used for grinding, drilling, screwing, and other operations on workpieces; the broken lines in the drawings depict portions of the double-headed hand-held power tool that form no part of the claimed design.

1 Claim, 8 Drawing Sheets
